UNITED STATES PATENT OFFICE.

JOHN F. McGLOTHERN, OF SEATTLE, WASHINGTON.

DESIGN FOR A ROCKING CHAIR.

Application filed July 15, 1924. Serial No. 10,155. Term of patent 7 years.

To all whom it may concern:

Be it known that I, JOHN F. McGLOTHERN, a citizen of the United States, residing at Seattle, in the county of King and State of Washington, have invented a new, original, and ornamental Design for Rocking Chairs, of which the following is a specification, reference being had to the accompanying drawing, forming part thereof.

The drawing is a view in perspective of a rocking chair, showing my design.

I claim:

The ornamental design for a rocking chair, as shown.

JOHN F. McGLOTHERN.
